UNITED STATES PATENT OFFICE

FREDERICK W. VODOZ, OF WILMETTE, ILLINOIS

AUTOMATIC STOKER

Application filed May 2, 1927. Serial No. 188,228.

This invention relates to improvements in automatic stoking devices for furnaces and has for its principal object to provide for an improved form of stoker and automatic controlling means therefor.

More specifically, my invention contemplates the provision of a stoker, automatically responsive to the weight of the unburned coal and ash carried on the grate bars, the arrangement being such that when a predetermined amount of fuel is consumed in the furnace and the total weight of the furnace charge carried by the grate drops below a predetermined value, the stoking system operates automatically to shake down the ash, break up the clinkers, spread the surface coal and to recharge the furnace with new coal in predetermined amounts sufficient to restore the furnace charge to a predetermined weight. A further object of the invention is to provide, in conjunction with the stoking apparatus, an improved ash removing system whereby the entire operation of charging the furnace and removing the ashes will be automatic and independent of the draft control devices, which may be either manually or thermostatically operated to cause the fire to burn with varying degree of intensity so as to give more or less heat as desired.

The invention may best be understood by referring to the accompanying drawings, in which

Figure 1 is a view in part elevation of a furnace of the ordinary household type to which my invention has been applied, with parts broken away to show certain details of the operating mechanism.

Figure 2 is a view somewhat similar to Figure 1, but showing the mechanism in vertical section taken on a line passing through the axis of the main operating and charging shaft.

Figure 3 is an end view of a stoking apparatus, taken on line 3-3 of Figure 1.

Figure 4 is a detail view of the charging carriage taken on line 4-4 of Figure 2.

Figure 5 is another sectional detail view of the charging carriage taken on line 5-5 of Figure 2.

Figure 6 is a detail sectional view of the grate bars taken on line 6-6 of Figure 1.

Figure 7 is a fragmentary plan view of the stoking apparatus with the storage hopper and other parts removed to show details of the charging carriage and spreader carried thereby, and

Figure 8 is a detail view of the main switch controlling mechanism showing in dotted lines the position of the parts when said switch is initially closed to start the forward movement of the charging carriage.

Figure 9 is a diagrammatic view of the actuating mechanism showing the parts in position when the carriage has partially completed its forward feeding movement.

Figure 10 is a view showing the carriage in its extreme forward position, and the motor reversing switch actuated to cause the carriage to be retracted.

Figure 11 is a view showing the carriage in fully retracted position, but with the grate still not fully loaded, in which case the main motor switch remains closed, and the reverse switch is actuated to move the carriage inwardly with a new load.

Figure 12 is a view similar to Fig. 11, but in which the grate has been fully loaded, and the parts are in position to cause the main motor switch to open, and thereby discontinue further charging of fuel.

Figure 13 is a diagrammatic view of the electric motor control circuit, including the main and reversing switches.

Referring now to details of the device illustrated in the drawings and embodying one form in which my invention may be utilized, 10 indicates a hot-air furnace of the ordinary household type, having an outlet flue 11 and an inlet draft opening 12 communicating with a fire-pot 13 in the usual manner. It will, of course, be understood that this specific type of furnace is utilized merely as a means of illustration of my invention, but that my improved stoking device can, with slight modification, be utilized in connection with a wide variety of coal-burning furnaces utilized not only for heating houses, but in steam generating plants and the like.

In carrying out my invention, I provide a

grate 15 which, in the form shown, is substantially circular so as to conform with the shape of fire box 13. Said grate is mounted for floating movement relative to the fixed 5 portions of the furnace and fire box, and is suitably counterbalanced so as to be responsive to changes in weight of fuel thereon. In the form herein illustrated, said grate is supported on a counterbalancing lever system al- 10 though other counterbalancing devices similar to those used in scales of various types, may also be employed. As shown herein, the counterbalancing system includes a lever 16 integral with said grate, and extending in 15 a horizontal direction through one wall of the furnace and pivotally connected on pivot pin 17 to a suitable support 18 on the exterior of the furnace. The counterbalancing system also includes a compression spring 20 in- 20 terposed between the free end of the lever 16 and a fixed overhead support 21 which herein forms the bottom of the charging carriage, as will hereinafter more fully appear. Means for adjusting the tension on spring 20 is pro- 25 vided, herein consisting of a bolt 23 threaded in the lever 16 and upon which the lower end of spring 20 is seated. Further adjustment of the relative position of the lever system and counterbalancing tension on the spring 30 20 may be afforded by mounting the pivot pin 17 of said lever on a threaded member 24 so that it can be adjusted vertically in support 18.

The surface of grate 15 is provided with a 35 plurality of apertures 26, 26, and in some of these apertures is mounted a plurality of rocking members 27, 27 pivoted on horizontally disposed bars 28, 28 in said grate and with their upper surfaces normally disposed 40 substantially flush with the upper surface of said grate, as is best shown in Figures 1 and 6. These rocking members have arcuate outer margins so as to permit them to rock upwardly on their pivot pins so that the 45 upper surfaces thereof project above the upper surface of grate 15, for the purpose of breaking up any clinkers which are formed adjacent the grate and also to agitate the ashes adjacent the grate and thus effectively 50 shake down the fire. Rocking movement of the members 27, 27 is preferably limited by stops 30, 30 which engage the under surface of the grate. Each of these rocking members 27 is pivotally connected to a rearwardly 55 extending bar 31, the nearest row of rocking members being directly connected to said bar, while the more remote rows of rocking members are connected to said bar and to each other by links 32, 32. The rear end of the bar 60 31 is connected to a lever 33 normally arranged in substantially upright position and pivoted at 34 to one side of the coal hopper 35. Means for actuating the lever 33 and grate members 27, 27 herein comprises a 65 spring 36, in cooperation with movement of

the stoking mechanism, as will hereinafter appear.

The outer end of the grate supporting lever 16 is provided with a pin 37 which moves in slotted end 38 of link 39. Said link is pivotally connected at 40 with a lever 41 which is in turn pivoted on pin 42 and projects inwardly toward the furnace and is yieldably held in raised position by a spring 43 connected to the side of the hopper 35. The 70 lever 41 is provided with a detent 45 which is normally adapted to engage a pin 46 extending inwardly from lever 33, as best shown in Figures 1, 5 and 7.

A rod 47 is connected to the end of lever 41 and extends upwardly to switch lever 48 on an electric control switch 49. This switch controls the circuit of electric driving motor 50, as will hereinafter more fully appear.

The fuel charging mechanism comprises a carriage 51 slidably mounted in a casing 52 disposed beneath the coal hopper 35. Said casing forms a passageway having discharge opening 54 at its inner end, disposed at one side of and within the fire box 13 directly 55 over the grate 15 as clearly shown in Figures 1 and 2. The carriage 51 consists of a plurality of baffle plates 55, 55 carried on the inner end thereof, and an impeller member 56 spaced horizontally from said baffle plates 60 by connecting bars 57, 57 so as to form a compartment 58 for the coal. The impeller member 56 is preferably made up of two parts 59 and 60, divided on horizontal plane. The lower part 60 is rigid with baffle plates 55 65 and connecting bars 57 and has a part 61 adjacent its rear end, having threaded engagement with screw shaft 62. Rotation of the screw shaft 62 in opposite directions positively reciprocates the lower impeller portion 60, together with baffle plates 55 and connecting bars 57, for feeding the coal in compartment 58 to the fire, and to withdraw said carriage again to its rearmost position 70 for a new charge of coal.

The upper portion 59 of the impeller member 56 is yieldably mounted on the lower member 60 so that excessive pressure on the front face of member 59, as for instance, by the wedging of coal between said impeller member and the front lower margin 63a of passage 63 from the superimposed coal hopper 35, will permit uninterrupted operation of the charging carriage. In the form shown the yieldable means comprises a series of 75 balls 65, 65 carried by the upper member 59, and adapted to ride on corrugated upper surface 66 of the lower impeller member 60 under tension of springs 67, 67. The tension of springs 67, 67 is adjusted so that upper 80 impeller member 59 will be carried with lower member 60 under ordinary operating conditions, but when unusual obstructions are met with, such as the lodgment and jamming of a piece of coal in the passageway 63 com- 85

5 municating from the hopper as described, the lower impeller member 60 forming the main part of the carriage is permitted to slide longitudinally relative to the upper member 59, and thus deliver at least a partial charge of coal to the fire. During the return movement of the parts, however, the normal superimposed relation of impeller parts 59 and 60 will be restored and the obstruction will 10 usually be removed with the next charge of coal which drops downward through opening 63 into the charging compartment 58 of the carriage.

15 The threaded shaft 62 which causes reciprocal movement of the carriage as aforesaid is driven by a worm wheel 70, which meshes with worm 71 on motor shaft 72 of motor 50.

20 In connection with the charging carriage I also provide automatic spreading means 25 for the coal, herein consisting of a forked arm 75 pivotally mounted on support 76 carried on the discharge end of the carriage 51. Said support 76 extends upwardly so that the pivotal axis 77 of spreader arm 75 is disposed 30 above the upper margin of discharge passage 54. A detent 78 is disposed adjacent the pivotal axis of said arm and adapted to engage a projection 79, forming an extension of the upper margin of discharge opening 54 (see 35 Fig. 1). The arrangement is such that when the carriage is in fully retracted position as shown in Figures 1 and 2, the spreader arm 75 will be raised and maintained in substantially horizontal position above the fire by the engagement of detent 78 and projection 79. As soon as the carriage is moving outwardly, however, the spreader arm 75 is permitted to fall by gravity into a substantially vertical position, as indicated in dotted lines in 40 Figure 2. In this position said arm engages the uppermost layers of coal and serves to spread the fire horizontally, as will hereinafter be more fully described.

45 As a part of the controlling means for the charging carriage, I provide a pin 80 connected at one side of the lower impeller member 60 and extending laterally through slot 81, formed in casing 52, as is best shown in Figure 5. A cocking lever 82 is pivotally mounted 50 on pin 80 outside of the casing 52 and normally extends in a rearward position, riding on the pin 46 carried by lever 33. The lever 82 is provided with a detent 84 which, under certain conditions, is adapted to engage the pin 46 and to carry it into locking position 55 with respect to detent 45 carried by lever 41. A chain 85 connected with an upwardly extending part 86 on lever 82 is adapted to trip and disengage said lever from pin 46 when the carriage is in fully retracted position, as will hereinafter be described. A projection 83 is provided on the upper side of lever 82 to automatically turn off the main power switch 49, as will also be more fully described. 60 The outer end of pin 80 has a horizontally

disposed rod 90 passing therethrough. This rod is connected with the operating lever 91a of an electric reversing switch 91 and is provided with two stops 92 and 93 at opposite ends thereof which are engageable by pin 80 70 at both forward or return limits of reciprocal movement of the carriage as to automatically reverse the direction of current in electric motor 50 at both, and thus produce corresponding reversible movements of said carriage. 75

The controlling mechanism for the main power switch 49 is best shown in Figure 8, and includes a plunger 94 engageable by projection 83 on lever 82, vertically movable in a support 94a and having a clevis 95 slidably mounted on its upper end. A coil spring 95a is connected between said clevis and a collar 96 fixed on said plunger. The clevis is pivotally connected to a lever 97 connected to switch 49 on the side opposite lever 48. Lever 48 is provided with a pin 48a movable vertically in slot 47a on the upper end of switch operating rod 47. 80

85 The electrical system for controlling the motor 50 includes main power switch 49 and reversing switch 91, both of the ordinary snap or quick acting type well known in the art, and their circuit connections are shown diagrammatically in Fig. 13. From this figure it will be seen that when the main switch lever 97 is raised the switch contact 117 is open, cutting off all power to the motor from the main supply line 115. When contact 117 is closed the circuit may be established through the motor armature 119 in forward or reverse direction, depending upon the position of reversing switch lever 91a which controls contact segments 121 and 122 of reversing switch 91. In the position of the switch lever 91a, shown in Fig. 13, the circuit is established through conductor 116, field winding 118, and conductor 120, and from thence through segment 132, conductor 123, armature 119, conductor 124, segment 121 to main line 125. When the switch lever 91a is shifted in a counter-clockwise direction, however, as shown in Fig. 10, the current through the armature 119 is reversed so as to reverse the direction of rotation of the motor. The circuit is then established from conductor 120 through segment 121, conductor 124, armature 119, conductor 123, segment 122 and thence to main line 125. 100

105 The cycles of operation of the various controlling devices above described may be described in connection with Figs. 1, and 8 to 12, both inclusive, as follows:

110 When the weight of the coal sustained on grate 15 has been sufficiently reduced, owing 125 to combustion, so as to cause unbalancing of the lever 16, the outer end of said lever moves downwardly and carries with it link 39 and inner arm of lever 41. This movement of lever 41 releases detent 45 from pin 46 as 120 130

shown in Fig. 8, whereupon tension of spring 36 causes the rocking members 27, 27 in grate 15 to be moved upwardly above the surface of said grate, as shown in Fig. 9 and agitate the ashes thereon, and cause the same to fall through the grate into the ashpit. At the same time, these rocking members 27, 27 serve to break up any clinkers that might have formed adjacent the grate.

- 10 Simultaneously with the tripping of lever 41 the control lever 48 of electric power switch 49 will be closed by upward movement of operating rod 47 as shown in dotted lines in Figs. 8 and 9. The spring 95a on plunger 94 is sufficiently light to be readily overcome and compressed by movement of the grate balancing system in case said plunger engages projection 83 on lever 82. This starts the motor 50 so as to rotate screw shaft 62 and cause the carriage 51 to be moved inwardly with its charge of coal contained in the compartment 58. The pin 80 and lever 82 are carried with the carriage during its movement as shown in Fig. 9, it being noted 25 that the chain 85 will be slackened as soon as the inward movement of the carriage is begun to permit the lever 82 to fall by gravity upon pin 46 carried by lever 33. It will be understood that the latter lever with its pin 30 will be in released position and swung to a position toward the furnace. The initial movement of the carriage also permits the spreader arm 75 in the furnace to drop in substantially vertical position and engage 35 the upper surface to spread any excess fuel toward the furthermost wall of the fire box. As soon as the baffle plates 55 have passed beyond the end of the discharge opening 54, the coal contained in compartment 58 is free to 40 drop between and around the connecting bars 57 onto the top of the fire. The inward movement of the carriage continues to a predetermined position where all of the coal may be discharged therefrom. This position is determined by the engagement of the outer end of pin 80 at one side of the carriage with stop 93 adjacent the reverse switch lever 91a, whereupon further inward movement of said carriage moves the said lever 91a to actuate reversing switch 91, as shown in Fig. 10 which immediately causes reversal in the direction of rotation of the motor 50 and a corresponding reversal of movement of the carriage so as to retract the same. During this retractive movement of the carriage, the lever 82 is still in engagement with and resting on pin 46 carried by arm 33, and detent 84 on lever 82 thereupon engages pin 46 and carries it to a position behind detent 45 on lever 41 so as to restore arm 33 with the rocking members 27 in normal position, as shown in Figure 1. After lever 82 has thus restored pin 46 behind detent 45, as described, the chain 85 becomes taut and raises lever 82 with its detent 84 out of engagement with pin 46,

as shown in Figure 11. Pin 80 carried by the charging carriage also engages stop 92 on rod 90 at the end of its retractive movement so as to again reverse the electric connections for the motor through switch 91.

70 In the event that the single charge of coal inserted in one reciprocal movement of the carriage is sufficient to restore the equilibrium of the counterbalancing system, link 39 will be moved upwardly and rod 47 will be moved downwardly, but by reason of the slotted end 47a of the latter, the position of switch lever 48 will not be disturbed until projection 83 on lever 82 is raised into engagement with plunger 94, and compresses spring 94a thereon as shown in full lines in Fig. 12. The pressure of said spring is sufficient to throw power switch lever 97 of switch 49 as seen in dotted lines in Fig. 12 so that the motor 50 will stop, with all of the parts now restored to their initial starting position as shown in Fig. 1. But in the event that the single charge is not sufficient to establish equilibrium of the counterbalancing system, the rod 47 remains up, as seen in Fig. 11, and 80 also holds up switch arm 48a (overcoming and fully compressing spring 94a), and thus maintains the electrical connections through switch 49 so that the motor will continue to run, but in reversed direction, owing to action of the reversing switch 91, as described. A second reciprocal movement of the carriage will thus immediately follow, as well as a second shaking movement of the rocker members 27, 27 on the grate, in the same manner as before. Both the loading and shaking operations will therefore be repeated automatically until the full predetermined weight of coal is deposited on the grate, whereupon further charging will be discontinued by actuation of the main power switch 49 when the carriage next reaches its retractive limit of movement, as shown in Fig. 1. In case of emergency, the mechanism may be manually operated in either direction, by means of 100 crank 50a shown in dotted lines.

105 The means for automatically feeding coal from storage hopper 35 to delivery passage 63 leading to the charging carriage, comprises a screw conveyor 100 mounted on shaft 101 having sprocket 102 at its outer end, provided with ratchet connection 103 to drive the shaft 101 in one direction only. The sprocket 103 is connected to sprocket 104 on the same shaft 62 which forms the 110 screw operating device for the charging carriage 51. By means of the ratchet connection 103, just described, the screw conveyor 100 will be operated in one direction only, preferably when the shaft 62 is operating to retract the charging carriage in unloaded condition. In this manner the conveyor can only be driven in a direction to carry the coal toward the loaded passage 63 and furthermore, the motor is called upon to operate the con- 115 120 125 130

veyor only at times that the carriage is being retracted and, therefore, is under the least load. Similar mechanical means are provided for discharging the ashes in the ash-pit as shown herein. This means comprises a screw conveyor 105 having one end extending beneath the ash-pit of the furnace and the other end passing over a storage pit 106, into which removable boxes are arranged at 10 a point removed from the ash-pit so as to permit the ashes to be readily withdrawn from said pit. In connection with said storage pit I provide a plurality of separate containers 107, 107 arranged side by side, but removable individually. The screw conveyor 105 is driven through sprocket 108, chain 109 and sprocket 110, provided with a ratchet connection 111 on shaft 62, which also permits driving engagement with the conveyor 20 in one direction only, and preferably when the charging carriage is being retracted.

I claim as my invention:

1. In a stoking device, and in combination with a fire box, a grate, shaking means for 25 said grate, and means responsive to a drop in weight of fuel on said grate below a predetermined value for actuating said shaking means.

2. In a stoking device, and in combination 30 with a fire box, a grate, counterbalancing means connected with said grate, shaking means for said grate, and means controlled by said counterbalancing means for actuating said shaking means when the weight of fuel 35 in said grate is reduced below a predetermined value.

3. In a stoking device, and in combination with a fire box, a grate, a reciprocably movable fuel feeding carriage, counterbalancing 40 means connected with said grate and responsive to a drop in weight of fuel thereon below a predetermined value, a motor operatively connected with said fuel feeding carriage, and control means for said motor responsive to a 45 predetermined condition of said counterbalancing means for feeding said carriage and discharging fuel into said fire box.

4. In a stoking device, and in combination 50 with a fire box, a grate, a reciprocably movable fuel feeding carriage, counterbalancing means connected with said grate and responsive to a drop in weight of fuel thereon below a predetermined value, a motor operatively connected with said fuel feeding carriage, and 55 control means for said motor responsive to a predetermined condition of said counterbalancing means for imparting a feeding movement to said carriage to discharge fuel into said fire box, and returning said carriage to its initial loading position.

5. In a stoking device, and in combination 60 with a fire box, a grate, a reciprocably movable fuel feeding carriage, counterbalancing means connected with said grate and responsive to a drop in weight of fuel thereon below

a predetermined value, a motor operatively connected with said fuel feeding carriage, and control means for said motor responsive to a predetermined condition of said counterbalancing means for imparting a feeding movement to said carriage to discharge fuel into said fire box, and returning said carriage to its initial loading position, said control means including a power switch operatively connected with said counterbalancing means, 75 and a power reversing switch automatically operated at the forward limit of its reciprocable movement.

6. In a stoking device, and in combination with a fire box, a grate, a reciprocably movable fuel feeding carriage, counterbalancing means connected with said grate and responsive to a drop in weight of fuel thereon below a predetermined value, a motor operatively connected with said fuel feeding carriage, 80 and control means for said motor responsive to a predetermined condition of said counterbalancing means for imparting a feeding movement to said carriage to discharge fuel into said fire box, and returning said carriage to its initial loading position, said control means including a power switch operatively connected with said counterbalancing means, 85 and a power reversing switch automatically operated at the forward limit of its reciprocable movement.

7. In a stoking device, and in combination with a fire box, shaking means, a motor for positively actuating said shaking means, power connections for said motor including 100 a control device, a floating grate responsive to variation in weight of fuel thereon and having operative connection with said control device for causing said shaking means to be actuated in a predetermined position of elevation of said grate.

8. In a stoking device, and in combination with a fire box, shaking means, a motor for positively actuating said shaking means, power connections for said motor including 110 a control device, a floating grate responsive to variation in weight of fuel thereon and having operative connection with said control device for causing said shaking means to be actuated in a predetermined position of elevation of said grate, and means for automatically shutting off said motor when the grate has been restored to a predetermined position of depression.

Signed at Chicago, Illinois this 30th day of 120 April, 1927.

FREDERICK W. VODOZ.
